Primary Examiner — John A Voytek(74) *Attorney, Agent, or Firm* — Standley Law Group LLP; James L. Kwak; Adam J. Smith(57) **CLAIM**

The ornamental design for a vehicle tire tread, as shown and described.

DESCRIPTION

FIG. 1 is an outside perspective view of a vehicle tire tread showing our design, it being understood that the depicted tread pattern extends over the entire circumference of the tire;

FIG. 2 is front elevational view thereof;

FIG. 3 is a rear elevational view thereof;

FIG. 4 is an outside elevational view thereof;

FIG. 5 is an inside elevational view thereof;

FIG. 6 is a top view thereof; and,

FIG. 7 is a bottom view thereof.

In the drawing figures, the tire features shown in broken lines indicate environmental subject matter only, and form no part of the claimed design.
